(57) **CLAIM**

The ornamental design for a external component for a foldable toy building, as shown and described.

DESCRIPTION

FIG. 1 is a front perspective view of a external component for a foldable toy building, showing my new design in an assembled configuration;

FIG. 2 is a rear perspective view thereof in the assembled configuration;

FIG. 3 is a front elevational view thereof in the assembled configuration;

FIG. 4 is a back elevational view thereof in the assembled configuration;

FIG. 5 is a left elevational view thereof in the assembled configuration;

FIG. 6 is a right elevational view thereof in the assembled configuration;

FIG. 7 is a top plan view thereof in the assembled configuration;

FIG. 8 is a bottom plan view thereof in the assembled configuration; and,

FIG. 9 is a top plan view thereof, in a flat, unassembled configuration.

The windows and door portion shown in broken lines are unclaimed environment, and form no part of the claimed design.
